UNITED STATES PATENT OFFICE

MAXIM KRONFELD, OF NEW YORK, N. Y.

BOOK-COVER PROTECTOR

Application filed May 7, 1929. Serial No. 361,187.

This invention relates to book cover protectors, and is applicable to books having stiff or semistiff covers, whether the object be to protect the book or to improve the appearance thereof. The cover protector herein contemplated may have suitable ornamentation thereon, and may carry a design and a label to receive the title of the book and the name of the owner thereof.

10 An object of the invention is to provide a book cover protector that is rugged and efficient, inexpensive to manufacture and easy and convenient to apply and use. Another object is to provide a cover protector which 15 is adjustable with relation to the thickness of the book to be covered thereby and having improved means to secure the same to a book.

20 A further object of the invention is the provision of improved flap means for engaging the cover protector with the inside faces of the covers of a book.

25 Other objects and advantages of the invention will become apparent as the specification proceeds.

With the aforesaid objects in view, the invention consists in the novel combinations and arrangements of parts hereinafter described in their preferred embodiments, 30 pointed out in the subjoined claims, and illustrated on the annexed drawing, wherein like parts are designated by the same reference characters throughout the several views.

In the drawing:

35 Figure 1 is a plan view of one pocket portion of the cover protector, embodying the invention.

Fig. 2 is a plan view of the second pocket portion of the cover protector.

40 Fig. 3 is a plan view of the assembled cover protector in flat open position with the book removed.

45 The advantages of the invention as here outlined are best realized when all of its features and instrumentalities are combined in one and the same structure, but, useful devices may be produced embodying less than the whole.

50 It will be obvious to those skilled in the art to which this invention appertains, that

the same may be incorporated in several different constructions. The accompanying drawing, therefore, is submitted merely as showing the preferred exemplification of the invention.

55 Referring in detail to the drawings, the book cover protector may be made of a pair of blanks 10 and 11, which may be built up into pocket portions 10a and 11a for receiving the covers of a book. The blanks may 60 be made of any suitable material, for example paper.

The blank 10 is provided with alined sections A, B, C separated by parallel fold lines 12, 13. The sections B, C may be coextensive in size with the book cover, while the section A is of sufficient size to extend around the back of the book and engage the pocket portion 11a. At the side of the section B there may be provided flaps D along fold lines 14, for folding over on the inside of a book cover. Edges 15, 16 of the flaps D may be cut along an angle to afford clearance in the assembling and application of the cover protector to a book. The flap C may have 70 reentrant angular edges 17 parallel to the edges 16. Intermediate of the edges 17 and spaced inward of the ends 18 of the flap C, is a flaplet 19 that projects toward said ends. Differently stated, it will be perceived that 75 the flaplet is integral with the blank 10 and intermediate of the side flaps D. Adhesive is supplied to the flaplet at 20 and also at 21 to the section C. Adhesive may also be applied to an edge portion 22 of the section A. 80

85 The blank 11 is constructed in all respects similarly to blank 10, except that section A is omitted.

In assembling the cover protector on a book, 90 sections B are placed against the outside of the book cover, flaps D turned inward over the same, and section C turned inward over flaps D and secured thereto with the adhesive. Then the flaplets 20 may be secured to the inside face of the book cover. Finally, the section A is folded around the back of the book 95 and secured with its adhesive to the pocket portion 11a, completing the cover protector.

100 It will be seen that since the flaplets 20 are small, the cover protector may be secured to

the book cover at small areas only, so that the book may not be mutilated especially when the cover protector becomes worn out and is replaced. The flaplets 20 facilitate assembling the cover protector snugly around the book, and as they afford a secure non-stretching engagement, the cover protector is always neatly and reliably retained on the book, and cannot be lost or accidentally removed, thus assuring constant protection for the book cover.

Having thus described my invention, I claim as new and desire to secure by Letters Patent:-

15 1. A book cover protector comprising two separate sections each having a pocket for individually receiving one cover of a book, one of the sections having a large flap to extend around the back of the book and engage 20 the other section, both sections having integral small inside projecting flap portions for attachment to the inside surfaces of the covers of the book, whereby the sections are retained in engagement with the book covers, 25 particularly at the free ends of the latter.

2. A book cover protector comprising two separate sections, each of said sections having spaced side flaps and one end flap joined together to form a pocket for each section, each 30 of said end flaps having a small integral flap projecting therefrom intermediate the side flaps, the small flaps having adhesive on their inner surfaces, one of the sections having a large flap opposite to its end flap for engaging 35 the other section at a point remote from its small flap.

3. A book cover protector comprising pocket portions for receiving the covers of the book, each of said pocket portions having 40 an integral non-stretching flaplet, said flaplet having adhesive to engage the said cover, whereby each pocket portion is retained in engagement on the book covers in the open and closed position of the book.

45 In testimony whereof I have signed my name to this specification.

MAXIM KRONFELD.
